CLAIM

The ornamental design for a compression arm sleeve, as shown and described.

DESCRIPTION

FIG. 1 is a perspective view of the compression arm sleeve of this invention;

FIG. 2 is a top plan view of the compression arm sleeve of this invention;

FIG. 3 is a lateral side elevation view of the compression arm sleeve of this invention;

FIG. 4 is a medial side elevation view of the compression arm sleeve of this invention;

FIG. 5 is a bottom plan view of the compression arm sleeve of this invention;

FIG. 6 is a front elevation view of the compression arm sleeve of this invention; and,

FIG. 7 is a rear elevation view of the compression arm sleeve of this invention.

In FIGS. 1-7, the broken lines showing a portion of the arm bearing the compression sleeve and hand form no part of the claimed design. In FIGS. 1-7, the broken lines showing the FJ logo on the surface of the compression sleeve form no part of the claimed design.

The interlocking "F and J" symbol on the arm of the sleeve is a registered trademark of Acushnet Company.

1 Claim, 4 Drawing Sheets
